BOOSTER DEVICE FOR OPERATING
WELL TOOLS

Thomas M. Ragan, Downey, Calif., assignor to
Baker Oil Tools, Inc., Vernon, Calif., a corpora-
tion of California

Application July 14, 1947, Serial No. 760,851

16 Claims. (Cl. 166—11)

1

This invention relates to well tools, and more particularly to the operation of mechanisms forming part of such tools, which are especially employable in connection with the cementing, acidizing, washing, production, etc., of oil and gas wells.

Certain well tools depend upon the engagement of devices with the wall of a well conduit, such as a well casing or liner, for effecting operation and control of the tool. For example, a drag device may engage a wall of a well casing, and through its resistance to movement within the casing produce operation of other parts of the well tool, such as the movement of slips and packing members from retracted to expanded condition against the well casing, or the opening or closing of a valve mechanism.

The frictional force available in effecting movement of such elements may sometimes be inadequate, resulting in inability to operate the well tool in the desired manner. This may be pronounced in connection with a valve device operable to control the flow of cement slurry pumped down a tubing string for deposition behind the well casing and into the formation. Specifically, a well tool may embody a downwardly seating valve, which is movable upwardly to open position in dependence upon movement of the tubing string and the frictional engagement of a drag device with the wall of the well casing. If it is desired to flush a relatively extended head of cement slurry, or the like, from the interior of the tubing string, such head may prevent opening of the valve device, since it imposes a much greater force on the valve tending to keep it closed than the frictional force of the drag device against the casing wall.

Accordingly, it is an object of the present invention to provide a well tool having relatively movable elements, in which the force available for moving such elements is multiplied.

Another object of the invention is to multiply the friction force of a drag device against the wall of the well casing, and utilize the enhanced effort for effecting movement of the well tool parts.

Still a further object of the invention is to provide a valve controlled well tool embodying a valve operating device capable of multiplying or boosting the force available for moving the valve between open and closed positions.

Yet another object of the invention is to provide a hydraulically controlled well tool valve apparatus embodying a hydraulic booster for effecting operation of the valve.

This invention has other objects which will be-

2

come apparent from a consideration of the embodiment shown in the drawings accompanying and forming part of the present specification. This form will now be described in detail to illustrate the general principles of the invention, but it is to be understood that such detailed description is not to be taken in a limited sense, since the scope of the invention is best defined by the claims appended hereto.

10 Referring to the drawings:

Fig. 1 is a longitudinal section through a well tool located in a well casing.

Fig. 2 is a longitudinal section, on an enlarged scale, through a valve device forming part of the tool disclosed in Fig. 1 with the valve illustrated in open position.

Fig. 3 is a side elevation of the lock device for determining the operation of parts of the tool.

The invention is disclosed in the drawings as applied to a well packer of a type designed to force fluid under pressure through the perforations of a well casing. It is to be understood, however, that it has application to other types of well tools.

25 Specifically, the well tool consists of a body 10, suitably secured, as by threading, to the lower end of a string of tubing or drill pipe 11, by means of which the tool is conveyed through the well casing 12 to the desired operating point therein. The body consists of an upper body member 13, a lower body member 14, and an intermediate body member 15 connecting the upper and lower members together in spaced relation. The general type of well tool shown is a packer described and claimed in the application of Charles E. Costello, Serial No. 391,548, filed May 2, 1941, for "Well Devices," now Patent No. 2,466,305.

30 The upper and lower portions of the tool are substantially duplicates, being connected to the intermediate body member 15 in opposed relation. A description of the upper portion should suffice for the lower portion as well.

35 The upper body member 13 includes an elongate mandrel or nipple 16 having a sub 17 screwed on its upper end, and a lower ported sub 18 secured to its lower end. One or more packing cups 60, 61 of rubber, or similar material, are suitably secured on the mandrel, with the lower cup 60 facing downwardly and the upper cup 61 facing upwardly. These packing cups are adapted for slidable sealing engagement with the wall of the well casing 12 to prevent both upward and downward flow of fluid between the upper body member 13 and the casing wall.

An upper by-pass tube 20 is positioned within the upper body member to provide an annular space 21 therewith. Its upper member is threaded into a by-pass T 22, which is suitably secured, as by welding, to the upper by-pass sub 17, through which it opens outwardly into the tubing-casing annulus 23 above the upper packing 61. The lower end of the by-pass tube 20 extends through an inner flange 24 on the lower sub 18, containing a rod packing 25 pressed in leak-proof engagement against the exterior of the tube by a suitable packing nut 26, to prevent downward flow of fluid through the annulus 21 beyond the flange 24.

As noted above, the construction of the lower tool portion is substantially the same as the upper, with the parts facing in the opposite direction, so that fluid passage between the lower body member 14 and casing wall in both upward and downward directions is prevented. Upward flow of fluid through the lower annulus 21a beyond the flange 24a is prevented by the flange 24a, packing 25a and packing nut 26a surrounding the lower by-pass tube 20a. For convenience in designation, the lower parts are numbered the same as the corresponding upper parts, with the suffix "a" added.

The upper and lower tool portions are held together in spaced relation by the intermediate body member 15, which actually forms part of the by-pass of the tool. This intermediate body member is secured to the upper and lower subs 18, 18a, and may be made of any length desired, depending upon the spacing required between the upper and lower packing cups 60, 60a. The by-pass around the packings extends from a point outside the tool below the lowermost packing 61a to a point outside the tool above the uppermost packing 61. More specifically, this by-pass passage is constituted by the lower T 22a, lower by-pass tube 20a, intermediate body member 15, upper by-pass tube 20, and upper by-pass T 22.

The upper sub 18 is provided with one or more upper outlets or ports 27 adjacent the packing cup 60 and flange 24, and the lower sub 18a is similarly provided with one or more lower outlets or ports 27a adjacent the lower packing cup 60a and flange 24a. Fluid cannot pass directly from the upper body annulus 21 to the lower body annulus 21a because of the flanges and packings around the by-pass tubes, but must pursue an indirect course. The fluid may be pumped downwardly through the tubing 11 into the upper body member annulus 21, exiting through the upper ports 27 into the localized annular zone 28 defined by the upper and lower packings 60, 60a, and by the intermediate body member 15 and casing 12. This fluid may flow downwardly through the zone 28 and enter the lower body member 14 through the lower ports 27a, where the fluid can pass downwardly through the annulus 21a around the lower by-pass tube 20a into the valve body or housing 29 screwed into the lower end of the lower sub 17a. The fluid may then pass through the valve outlets or ports 30 in the housing to the exterior 23a of the tool below the lower packing cup 61a, from where it may flow upwardly into the lower by-pass T 22a, through the lower by-pass tube 20a, intermediate by-pass member 15, tube 20 and upper by-pass T 22, into the tubing-casing annulus 23 above the upper packing cup 61.

The allowing of the fluid to pursue the course just described is dependent upon the control of

the fluid flow through the valve ports 30 at the lower end of the tool. Such control is obtained through a valve mechanism, including the valve body or housing 29. This valve mechanism includes a valve seat 31 clamped between the upper and lower portions 29a, 29b of the valve housing, which are threaded together. The seat is engageable by a valve head 32 upon downward movement of the latter. When such a valve head is in engagement with the valve seat, fluid cannot flow downwardly through the latter and out through the ports 30. However, in the specific valve disclosed in the drawings, fluid may flow in the reverse direction through the ports 30 and upwardly through the seat 31, since the force of fluid moving in such direction will automatically disengage the head 32 from the seat.

The valve mechanism further includes a valve stem or piston rod 33 threadedly secured to the head 32 and extending downwardly through the seat 31 into a large cylinder 34 formed on an intermediate portion of the valve housing 29, the rod being integral with, or otherwise secured to, a piston 35 carrying suitable piston rings or side seals 36 adapted to engage the wall of the large cylinder. The valve housing or body 29 includes a lower cylinder 37 of a substantially smaller diameter than the larger cylinder 34, in which a small-diameter elongate piston 38 is slidable, such piston carrying suitable side seals or piston rings 39 engageable with the wall of the small cylinder to prevent leakage therebetween.

The space 40, 41 between the large and small pistons 35, 38 within the large and small cylinders 34, 37 is filled with a suitable liquid 42, such as light oil, which may be inserted through a filler or bleeder hole 43, which is then closed by a plug 44.

The lower end of the piston 38 is threaded into the lower head 45 of a lock sleeve 46 extending upwardly around the piston 38 and slidable along the exterior of the small cylinder 37. This sleeve has a generally L-shaped slot therein, including vertical and horizontal slot portions 47, 48 adapted to receive a lock pin 49 secured to the small diameter cylinder 37. The rod 50 of a drag device 51 depends from the sleeve head 45, having a collar 52 and guide 53 threaded on its lower end. Suitable drag springs 54 are secured to the collar 52, being frictionally engageable with the wall of the well casing 12. Such springs extend upwardly along the rod 50 and are connected at their upper ends to an upper collar 55 slidable along the rod 50.

The drag springs 54 exert a certain frictional force against the wall of the well casing 12, and this frictional force is availed of to move the valve head 32 upwardly from the valve seat 31. The tubular string 11 and valve housing 29 connected thereto are movable as a unit longitudinally of the small piston 38, lock sleeve 46 and drag device 51, in order to effect movement of the valve head 32 relative to its cooperable seat 31. If the lock pin 49 is disposed within the longitudinal portion 47 of the L-slot, the housing 29, body 10 and tubing string 11 may be moved as a unit with respect to the aforementioned lock sleeve, small piston and drag device. Downward movement of the first-mentioned parts 29, 10, 11 produces relative upward movement of the piston 38 within the smaller cylinder 37, since movement of the former is resisted or prevented by the frictional engagement of the drag springs 54 with the wall of the well casing 12. Accordingly,

a unit pressure is developed in the entrapped liquid 42 within the cylinders 34, 37, which is exerted over the entire area of the large piston 35 in an upward direction, elevating the piston 35 and its attached head 32 from the valve seat 31. Conversely, upward movement of the tubular string 11, tool body 10 and valve housing 29 effects a relative lowering movement of the small piston 38 within its cylinder 37, and relieves the fluid 42 of pressure, allowing the valve head 32 to re-engage its seat.

Since the cross-sectional area of the small diameter piston 38 and cylinder 37 is substantially less the cross-sectional area of the larger diameter piston 35 and cylinder 34, the force imposed by the small piston 38 on the liquid 42 is multiplied many times upon the large piston 35, the multiplication in force being in the ratio of the large cylinder diameter to the small cylinder diameter. In other words, the frictional force of the springs 54 against the wall of the casing 12 is multiplied to the extent indicated upon the large diameter piston 35, and thereby provides a much greater elevating force upon the valve head 32.

When it is desired to maintain the valve head 32 elevated from its seat 31 upon raising of the tubing string 11 and well tool within the well casing 12 to hold the valve in open position, the tubing string 11, tool body 10 and housing 29 can be lowered until the lock pin 49 is aligned with the horizontal slot portion 48 of the lock sleeve 46, and the tubing string 11 then turned to the left part of a revolution to locate the pin 49 within such horizontal portion 48. During the lowering movement of the tool parts and tubing string, the pressure created in the entrapped fluid 42 raises the head 32 from its seat 31, and upon locking of the pin 49 within the horizontal slot portion 48, the fluid 42 in the cylinders 34, 37, as well as the pistons 38, 35 and valve head 32 are maintained in such elevated position, enabling the well tool to be elevated in the well casing 12 without permitting the valve head to close against its seat.

A representative use of the booster mechanism is in connection with the cementing of a well casing. The tool disclosed in Fig. 1 is lowered through the well casing 12 until the inner packing cups 60, 60a are disposed on opposite sides of casing perforations 59, through which cement slurry or other cementitious material is to be ejected. During this running-in operation, the drag springs 54 resist lowering of the piston 38 and lock sleeve 46 within the casing, and, accordingly, the valve head 32 occupies an upper position with respect to its seat 31. Actually, in the specific design disclosed in the drawings, it is immaterial what position is occupied by the piston 38 during the running of the tool within the well casing, since the valve head can automatically elevate from its seat and permit the fluid in the well casing to enter the tool through the ports 30. In any event, during lowering of the tool in the well casing, the relative upward movement of the small piston 38 within the small cylinder 37 positively forces the valve head 32 from its seat 31, through the intermediary of the entrapped oil 42, piston 35 and piston rod or valve stem 33.

After the tool has been properly located in the well casing with its packing cups 60, 60a disposed on opposite sides of the casing perforations 59, circulating fluids may be pumped down the tubing string 11 with the valve in its open posi-

tion, as illustrated in Fig. 2, passing through the upper annulus 21 and out through the upper ports 27 into the localized zone 28 between the packing members 60, 60a; thence into the lower ports 27a and lower annular passage 21a, and around the valve head 32 and through the ports 30 to a point below the lowermost packing member 61a. The fluid may then proceed upwardly through the by-pass passage 22a, 20a, 15, 20, 22, discharging into the tubing-casing annulus 23 above the upper packing member 61, for continued upward movement through such annulus to the top of the well bore.

15 A charge of cement slurry may be started down the tubing string 11 and when its lower end is near the well tool, the tubing string may be elevated several inches, say two or three inches, to move the valve housing 29 upwardly with respect to the piston 38 and lock sleeve 46, as permitted by the disposition of the lock pin 49 within the longitudinal slot portion 47 of the lock device, since the piston and lock sleeve are prevented from moving upwardly by the drag device 51. Such upward movement relieves the entrapped 20 liquid 42 in the cylinders 37, 34 of pressure and permits the fluid in the casing and well tool to seat the head 32 downwardly against the valve seat 31, preventing further downward passage of fluid around the valve head 32 and out through the ports 30. In other words, the ports 30 are closed to the passage of fluid between the interior of the well tool and the exterior of the well tool below the lowermost packing 61a.

25 The cement slurry passes from the lower end of 35 the tubing string 11, through the upper annulus 21 in the body and out through the upper ports 27, being forced under pressure through the casing perforations 59 for deposition behind the well casing 12. Such cement slurry cannot flow through the lower ports 27a into the lower body member 14, since the valve is in closed position and the fluid in the lower portions of the body member 14 is prevented from flowing down and out through the ports 30.

30 40 Following deposition of the required amount of cement slurry through the perforations 59, any excess may be flushed from the tool by lowering the tubing string 11, and the tool body 10 and valve housing 29 attached thereto, several inches, to effect relative upward movement of the piston 38 within its cylinder 37, the movement of such piston being transmitted through the entrapped body of oil 42 to the large diameter piston 35, causing the latter to move upwardly, and correspondingly moving the valve head 32 from its seat 31. If desired, the lock pin 49 at the lower end of the longitudinal slot portion 47 may be moved into the horizontal slot portion 48 of the lock sleeve 46 to prevent inadvertent elevation of the small cylinder 37 with respect to the small piston 38, which would permit the valve head 32 to re-engage its seat 31.

35 45 50 55 60 65 70 75 Washing fluid may now be pumped down the tubing string 11, forcing the cement slurry ahead of it and causing it to flow through the upper annulus 21 and upper port 27 into the localized zone 28, then through the lower port 27a and lower annulus 21a, and around the valve head 32, to discharge through the valve ports 30, whereupon the excess cement slurry followed by the washing fluid may flow through the by-pass passage 22a, 20a, 15, 20, 22 into the annulus 23 above the upper packing 61, for passage to the top of the well bore and appropriate disposal.

The cement slurry may also be disposed of by

circulating the washing fluid in a direction reversely to that described by initially pumping it down the tubing-casing annulus 23, the washing fluid passing through the by-pass passage and the ports 30 for upward flowing around the valve head 32, body passages 21a, 21 and ports 27a, 27 into the tubing string 11, carrying the excess cement slurry in the tubing string ahead of it to the top of the well bore.

In the event that the excess cement slurry in the tubing string is to be disposed of by pumping the washing fluid down the tubular string 11, conditions sometimes render it difficult to relatively move the valve head 32, or equivalent valve, to open position. For example, in the event that there is an extended column of excess cement slurry present in the tubing string of, say, 1,000 feet, the hydrostatic head of such cement slurry acting downwardly on the valve member exerts a downward closing force thereon which may be substantially greater than the force of friction of the drag springs 54 against the wall of the well casing 12. Downward movement of the tubing string 11, and attached body 10 and valve housing 29, might not, therefore, result in opening of the valve, if only the frictional force of the drag device 51 against the casing 12 were available for direct transmission to the valve head 32. However, by virtue of the present invention, the frictional force of such drag springs is multiplied many times, thereby making it possible to move the valve head 32 upward even with a very substantial hydrostatic head of cement slurry imposed thereupon.

As was noted above, the area A of the small cylinder is considerably less than the area B of the large cylinder. As a result, the small piston 38 can function to create a maximum unit pressure in the oil 42 within the cylinder spaces 40, 41, depending upon the maximum frictional force exerted by the drag springs 54 against the wall of the casing. This unit pressure is then imposed upon the large diameter piston 35, and since the latter has a much greater area than the smaller piston, a much greater total force is available to elevate the piston 35 and the valve head 32 than would be available if the small piston 38 were mechanically connected directly to the valve head 32. In effect, the small piston 38 and small cylinder 37 constitute a fluid pump for generating pressure in the liquid 42 within the cylinders 37, 34, and the large piston 35 and large cylinder 34 constitute a fluid motor receiving such liquid under pressure and employing such pressure for operating a well device; in this particular instance, a valve member.

After the cementing operation has been completed, the tubular string 11, tool body 10 and valve housing 29 may be lowered, which causes the fluid pump 37, 38 to operate to elevate the head 32 from its seat 31, whereupon the lock pin 49 can be turned into the horizontal lock portion 48 of its cooperable sleeve 46 and the entire tool then elevated from the well casing 12, the locking of the tool preventing bleeding of the oil 42 from the large cylinder 34 into the small cylinder 37, since downward movement of the small piston 38 within its cylinder is prevented. Accordingly, fluid may pass from within the tubular string 11 through the tool body 10 and around the valve head 32 for discharge through the ports 30 to a point below the well tool.

While the invention has been described with particular reference to a valve device, it is to be understood that it may be employed in general

as a force multiplier for increasing the effort available in operating well tool parts.

It is, accordingly, apparent that a well tool has been provided, in which the force available for operating well parts has been considerably multiplied, and which, when specifically related to a valve device for a well tool, overcomes to a large extent the pressure conditions within a tool tending to prevent operation of the valve device.

Having thus described my invention, what I claim and desire to secure by Letters Patent is:

1. In a subsurface well tool, relatively movable parts cooperable with each other to perform a function in a well bore while disposed in the well bore; means for effecting relative movement between said parts, comprising a fluid motor mechanism which includes a first hollow cylinder member and a first piston member relatively reciprocable in said first cylinder member, one of said first members being engageable with one of said parts to operate said one of said parts; said means further comprising a fluid pump mechanism which includes a second hollow cylinder member communicable with said first cylinder member and a second piston member relatively reciprocable in said second cylinder member, the cross-sectional pressure actuatable area of said second cylinder member being substantially less than the cross-sectional pressure actuatable area of said first cylinder member; a fluid in both of said cylinder members; and means in the well bore connected to a member of one of said mechanisms for bodily moving said member of said one of said mechanisms with respect to a member of the other of said mechanisms to generate a pressure in said fluid.

2. A well tool adapted to be lowered in a well bore on a running-in string, including relatively movable parts cooperable with each other to perform a function in said well bore while disposed in said well bore, a fluid motor engageable with one of said parts to move the same with respect to said other part, a fluid pump fluidly communicable with said motor, the pressure effective cross-sectional area of said pump being substantially less than that of said motor, and means connected to an element of said pump and operable in the well bore for positively displacing and bodily moving said pump element to develop a fluid pressure in said pump and in said motor to move said one of said parts.

3. A well tool adapted to be lowered in a well bore on a running-in string, including relatively movable parts cooperable with each other to perform a function in said well bore while disposed in said well bore, a fluid motor engageable with one of said parts to move the same with respect to said other part, a fluid pump fluidly communicable with said motor, the pressure effective cross-sectional area of said pump being substantially less than that of said motor, and means connected to said pump and operable by manipulation of said running-in string for generating a fluid pressure in said pump and motor.

4. A well tool adapted to be lowered in a well bore on a running-in string, including a valve seat, a valve head engageable with said seat, a fluid motor engageable with said head to move the same relative to said seat, a fluid pump fluidly communicable with said motor, means connected to an element of said pump and operable in the well bore for positively displacing and bodily moving an element of said pump to develop a fluid pressure therein and in said

motor, the pressure effective cross-sectional area of said pump being substantially less than that of said motor.

5. A well tool adapted to be lowered in a well bore on a running-in string, including a tubular member to be disposed in the well bore and having a valve seat, a valve head engageable with said seat, a fluid motor engageable with said head to move the same relative to said seat, and a fluid pump fluidly communicable with said motor, the pressure effective cross-sectional area of said pump being substantially less than that of said motor, and means connected to said pump and operable by manipulation of said running-in string for generating a fluid pressure in said pump and motor.

6. A well tool adapted to be lowered in a well casing on a running-in string, including relatively movable parts cooperable with each other to perform a function in said well casing, a fluid motor engageable with one of said parts to move the same, a fluid pump fluidly communicable with said motor and operable by manipulation of said running-in string, said pump comprising a hollow cylinder element and a piston element relatively reciprocable in said cylinder element, and means connected to one of said elements and engageable with the wall of the well casing to resist movement of said one of said elements therewithin, the pressure effective cross-sectional area of said pump being substantially less than that of said motor.

7. A well tool adapted to be lowered in a well casing on a running-in string, including relatively movable parts cooperable with each other to perform a function in said well casing, a fluid motor engageable with one of said parts to move the same, a fluid pump fluidly communicable with said motor and operable by manipulation of said running-in string, said pump comprising a hollow cylinder and a piston relatively reciprocable in said cylinder, and means connected to said piston and frictionally engageable with the wall of said casing to resist movement of said piston therewithin, the pressure effective cross-sectional area of said pump being substantially less than that of said motor.

8. A well tool adapted to be lowered in a well casing on a running-in string, including a valve seat, a valve head engageable with said seat, a fluid motor engageable with said head to move the same relative to said seat, a fluid pump fluidly communicable with said motor and operable by manipulation of said running-in string, said pump comprising a hollow cylinder element and a piston element relatively reciprocable in said cylinder element, and means connected to one of said elements and frictionally engageable with the wall of the well casing to resist movement of said one of said elements therewithin, the pressure effective cross-sectional area of said pump being substantially less than that of said motor.

9. A well tool adapted to be lowered in a well casing on a running-in string, a valve seat, a valve head engageable with said seat, a fluid motor engageable with said head to move the same relative to said seat, a fluid pump fluidly communicable with said motor and operable by manipulation of said running-in string, said pump comprising a hollow cylinder and a piston relatively reciprocable in said cylinder, and means connected to said piston and frictionally engageable with the wall of said casing to resist movement of said piston therewithin, the pres-

sure effective cross-sectional area of said pump being substantially less than that of said motor.

10. A well tool adapted to be lowered in a well casing on a running-in string, including a well packer body having an outlet, packing means around said body engageable with said casing, valve means connected to said body for controlling flow of fluid through said outlet, a fluid motor operatively connected to said valve means for operating said valve means, a fluid pump fluidly communicable with said motor and operable by manipulation of said running-in string, said pump comprising a hollow cylinder element and a piston element relatively reciprocable in said cylinder element, and means connected to one of said elements and frictionally engageable with the wall of said casing to resist movement of said one of said elements therewithin, the pressure effective cross-sectional area of said pump being substantially less than that of said motor.

11. A well tool adapted to be lowered in a well casing on a running-in string, including a well packer body having spaced packing means therearound engageable with said casing, said body having an outlet between said packing means, valve means connected to said body below said outlet for controlling flow of fluid through said outlet, a fluid motor operatively connected to said valve means for operating said valve means, a fluid pump fluidly communicable with said motor and operable by manipulation of said running-in string, said pump comprising a hollow cylinder and a piston relatively reciprocable in said cylinder, and means connected to said piston and frictionally engageable with the wall of said casing to resist movement of said piston therewithin.

12. A well tool adapted to be lowered in a well casing on a running-in string, including a well packer body having spaced packing means therearound engageable with said casing, said body having an outlet between said packing means, a valve housing connected to said body and having a valve seat therein communicable with said outlet, a valve head engageable with said seat, a fluid motor having means engageable with said head to move the same relative to said seat, a fluid pump fluidly communicable with said motor and operable by manipulation of said running-in string, said pump comprising a hollow cylinder and a piston relatively reciprocable in said cylinder, and means connected to said piston and frictionally engageable with the wall of said casing to resist movement of said piston therewithin, the pressure effective cross-sectional area of said piston being substantially less than that of said motor.

13. A well tool adapted to be lowered in a well bore on a running-in string, including relatively movable parts cooperable with each other to perform a function in said well bore, a fluid motor engageable with one of said parts to move the same, a fluid pump fluidly communicable with said motor and in substantial longitudinal alignment with and secured to said motor, means operatively connected to an element of said pump for resisting movement of said element in and relative to said well bore, said element being operable in response to movement of said motor and pump to develop a fluid pressure in said pump and motor, the pressure effective cross-sectional area of said pump being substantially less than that of said motor.

14. A well tool adapted to be lowered in a well

casing on a running-in string, including relatively movable parts cooperable with each other to perform a function in said well casing, a first hollow cylinder connected to one of said parts, a first piston relatively reciprocable in said first cylinder and connected to the other of said parts, a second hollow cylinder secured to said first cylinder and communicable therewith, a second piston relatively reciprocable in said second cylinder, means secured to said second piston and engageable with the wall of said well casing to resist movement of said second piston therewithin, the cross-sectional area of said second cylinder being substantially less than the cross-sectional area of said first cylinder.

15. A well tool adapted to be lowered in a well casing on a running-in string, including a valve seat, a valve head engageable with said seat, a first hollow cylinder connected to said valve seat, a first piston relatively reciprocable in said first cylinder and connected to said valve head, a second hollow cylinder secured to said first cylinder and communicable therewith, a second piston relatively reciprocable in said second cylinder, means secured to said second piston and engageable with the wall of said well casing to resist movement of said second piston therewithin, the cross-sectional area of said second cylinder being substantially less than the cross-sectional area of said first cylinder.

16. A well tool adapted to be lowered in a well casing on a running-in string, including a valve seat, a valve head engageable with said seat, a first hollow cylinder connected to said valve seat, a first piston relatively reciprocable in said first cylinder and connected to said valve head, a second hollow cylinder disposed below and secured to said first cylinder and communicable therewith, a second piston relatively reciprocable in said second cylinder, means secured to said second piston and engageable with the wall of said well casing to resist movement of said second piston therewithin, the cross-sectional area of said second cylinder being substantially less than the cross-sectional area of said first cylinder.

THOMAS M. RAGAN.
